UNITED STATES PATENT OFFICE.

PETER I. WOLD, OF EAST ORANGE, NEW JERSEY, ASSIGNOR TO WESTERN ELECTRIC COMPANY, INCORPORATED, OF NEW YORK, N. Y., A CORPORATION OF NEW YORK.

SWITCHING MECHANISM FOR VACUUM TUBES AND THE LIKE.

Application filed September 27, 1920. Serial No. 413,097.

To all whom it may concern:

Be it known that I, PETER IRVING WOLD, a citizen of the United States, residing at East Orange, in the county of Essex and 5 State of New Jersey, have invented certain new and useful Improvements in Switching Mechanism for Vacuum Tubes and the like, of which the following is a full, clear, concise, and exact description.

10 In certain electrical circuits in which it is desirable to maintain continuous action it frequently occurs that a piece or pieces of apparatus may be included which are subject to deterioration of one kind or another, 15 in which case it is necessary to replace the deteriorated element by another. Sometimes this deterioration may amount to a complete and sudden deterioration of the element rendering it totally useless, and at 20 other times the deterioration may be a gradual one in which, after a certain stage has been reached, it would be desirable to replace it by a new element. With such circuits it is ordinarily necessary to maintain 25 a continuous supervision over the elements in order to replace them at the proper time.

This invention relates to a means for the replacement of a piece of apparatus subject to such deterioration by another piece of the 30 same character to insure continuous operation. One of its objects is to make the action automatic, such that the replacement will occur whenever the element falls below a certain standard of operation. More specifically the invention relates to and has as 35 its object the provision of means for replacing a vacuum tube of the thermionic type in any circuit in which it may be contained, if and when the tube has deteriorated below 40 a certain standard.

In the case of vacuum tubes used as amplifiers or as detectors in various types of electrical circuits, the deterioration may be due to any one of a number of factors, but 45 probably the most important one is the practical destruction of the element due to the burning out of the filament, and unless an attendant is present at the time or is called by some signal there may be a serious 50 interruption in the service which the electrical circuit is intended to give.

The invention will be better understood by reference to the accompanying drawings in which Figure 1 shows a circuit arranged for carrying out the purpose of the inven-

tion. Figure 2 shows a modification of the circuit.

Referring more specifically to Figure 1 there is shown a circuit which might well be that of a standard telephone repeater 60 with input terminals at 1 and output terminals at 2, to which latter may be connected any suitable output circuit 3. These input and output terminals are connected to the corresponding terminals of a vacuum tube 65 repeater 4, this member comprising an evacuated vessel enclosing a heated filament 5, an anode 6 and a grid 7. The vacuum tube is connected to the circuit as a whole through the intermediary of a multiple 70 switch consisting of four movable members, G, F₁, F₂ and P. These are connected together by the member 8, preferably of insulating material, so as to form the multiple 75 switch. These four movable strips are 80 adapted to make contact with either of a group of terminals 10, 11, 12, and 13, or 20, 21, 22 and 23. The first group of these terminals are connected in the order given to the grid 7, the terminals of the filament 5 85 and the plate 6 of the vacuum tube 4.

The movable member G of the switch is permanently connected to one of the input terminals of the line and the member F₁ is connected to the other input terminal and 85 also to one pole of the filament heating battery A. The member F₂ is connected to the other pole of the heating battery A and also to the negative terminal of the plate battery B, which in turn is connected to one of the 90 terminals of the output circuit. The member P is connected through the magnetic coil 14 to the other terminal of the output circuit. The element 8 carries at one end an armature 15 and the electromagnet 14 is so 95 placed with respect to the armature 15, that, with the proper current flowing therethrough it will hold the switch in the operating position shown.

With the circuit as thus connected, the 100 filament 5 will be heated by the battery A and the output circuit will be supplied with voltage by the battery B. The normal space current, which will then be flowing through the tube, will pass through the coil 14 which 105 is so adjusted as to sensitivity that it is able, with the normal space current, to hold the switch in the position shown.

A second vacuum tube 24 is used as a supplementary tube to be used in case the tube 110

4 deteriorates beyond a certain point. This tube 24 is identical to the tube 4, possessing a filament 25, an anode 26 and a grid 27, but is normally entirely out of action. Its 5 terminals are connected to the group of contacts or terminals 20, 21, 22 and 23 placed on the opposite side of the movable switch members so that the grid, filament and plate terminals are connected respectively to the 10 contacts in the order given. In case the switch as a whole is moved from the first set of contacts to the second set, the tube 24 will occupy exactly the same position with respect to the circuit as a whole as the tube 15 4 originally did.

A spring 30 is connected to the switch tending to carry it into contact with the second set of contacts, but the switch is normally held in contact with the first set by 20 the space current flowing through the coil 14. If, however, a decrease in the space current flowing through the tube 4 occurs, the switch will be released when the current falls below a certain predetermined value, 25 and will, therefore, eliminate from the circuit the tube 4 and substitute in its place the tube 24. Upon this substitution the normal current will again be restored to the circuit as a whole and in particular to the coil 30 14, but the adjustment of the sensitivity of the coil can be so arranged that it will not be able now to restore the switch to its former position, mainly because of the increased distance between the coil 14 and the armature 35 15. In order to avoid any possibility of trouble in this direction, however, it will in general be desirable to have some locking arrangement by which the switch will be locked up in its second position and such a 40 mechanism is shown at 31.

Figure 2 shows a modification of the circuit. This circuit differs from the first only in a simplification of the switch, which in this latter case contains three movable switch 45 members and corresponding contacts instead of four. The terminals of the filaments 5 and 25, which in Figure 1, were shown as going to the contacts 11 and 21 respectively are joined together and connected permanently 50 to one pole of the heating battery A, and the movable member F_1 of the switch is eliminated. Aside from this feature the circuit arrangement and the operation is the same as that described in connection with Figure 1.

With the arrangement as set forth, it will not be necessary to maintain a close supervision of the electrical circuit so far as the deteriorating elements are concerned and an 60 occasional visit will show whether the first or second tube is in operation. In case the latter condition exists, the supervisor may, at his leisure, replace the first tube by a new one, and may then operate the switch 65 to bring it into its normal position, placing

the new tube in operation. The second tube, therefore, acts continuously in the capacity of a supplementary tube to be used in emergencies. In case it is desired a supplementary circuit may be supplied which upon operation 70 of the switch to throw in the second tube will be closed to operate a visual or audible signal, thus attracting the attention of the supervisor.

During operation of the circuit there will, 75 of course, be fluctuations in the space current due to the signal or other impulses impressed on the tube. Obviously the switch should be adjusted as to speed of action and sensitivity so as not to operate under such 80 fluctuations.

While this circuit has been described and explained as being adapted to take care of a change in the characteristics of the vacuum tube which shows itself as a decrease in the space current, it can be adapted to take care 85 of any exceptional change whether it be an increase or a decrease in the space current, and whether this change be due to one cause or another, by arranging the switch to act on 90 an underload or an overload.

Also while the invention has been described in connection with one form of an amplifier circuit, it is to be understood that it is not limited to this specific disclosure, 95 but may be used with any vacuum tube circuit whether the said tube is used for an amplifier, or a detector, or for other purposes, the principle involved in each case being that, upon the deterioration of one tube, there shall be an automatic cutting out of this tube and the substitution of a supplementary tube. Also, it is to be noted that while the invention has been described in connection with vacuum tubes, that the same 100 principle may be used in connection with a large variety of other types of apparatus.

What is claimed is:

1. An electrical circuit comprising a vacuum tube element having an anode and a 110 cathode, a second element of the same character, means for supplying space current to said first tube, means for supplying heating current to the filament of said first tube, and means responsive to the deterioration of said 115 first tube for replacing said first tube with said second tube and to connect both of said supply means thereto.

2. The combination of elements recited in claim 1 characterized further by the fact that 120 connections are provided whereby the means for substituting one tube for the other is operated by the space current flowing through the vacuum tube.

3. An electrical circuit comprising a 125 vacuum tube element, a second element of the same character, a source of space current for said elements, a switch mechanism normally holding the first vacuum tube in operational action, and means comprising a magnet coil 130

carrying the space current flowing through the first tube and associated with said switch for replacing the first tube by the second when the first tube has fallen below a certain standard.

4. The combination of elements recited in claim 3 characterized further by the fact that upon operation of the switch to substitute the second tube for the first, means are provided for locking it up in its second position.

5. The combination set forth in claim 3 and further characterized by the fact that the switch upon operation to substitute the second for the first tube, means are provided for locking it up in its second position.

6. A vacuum tube circuit adapted to receive incoming impulses and to transmit outgoing impulses, a three electrode vacuum tube element, a switching mechanism having a group of terminals to which the terminals of the said vacuum tube are connected, a plurality of contact elements on said switch, means for normally holding said elements in contact with the group of terminals, a supplementary group of terminals, a second vacuum tube having its terminals connected to said supplementary group of terminals and means for automatically moving the contact elements from the first group to the supplementary group of terminals when the

first tube has deteriorated below a certain standard.

7. The combination of elements recited in claim 6 characterized further by the fact that the means for moving the contact elements consists of a magnet coil.

8. The combination recited in claim 7 further characterized by the fact that connections are provided whereby the magnet coil normally carries the space current from the first tube and is so adjusted that when this current falls below a predetermined value the switch is operated to substitute the second tube for the first.

9. The combination recited in claim 8 further characterized by the presence of a locking mechanism adapted to lock up the switch when it has moved to its second position.

10. The combination set forth in claim 6 further characterized by the fact that the two groups of terminals have three contacts each, those in the first group being connected respectively to the grid, one terminal of the filament, and the plate of the first vacuum tube, those in the second group being similarly connected to the terminals of the second tube.

In witness whereof, I hereunto subscribe my name this 13th day of September, A. D., 1920.

PETER I. WOLD.
